G. W. HULSHIZER

VALVE FOR ROCK DRILLS

Filed June 20, 1925

UNITED STATES PATENT OFFICE.

GEORGE W. HULSHIZER, OF STEWARTSVILLE, NEW JERSEY, ASSIGNOR TO INGERSOLL-RAND COMPANY, OF JERSEY CITY, NEW JERSEY, A CORPORATION OF NEW JERSEY.

VALVE FOR ROCK DRILLS.

Application filed June 20, 1925. Serial No. 38,442.

This invention relates to fluid actuated rock drills, but more particularly to a spool type distributing valve for rock drills of the hammer type.

5 One object of the invention is to enable a rock drill to be equipped with a valve so constructed as to prevent centering of said valve.

10 Another object is to produce a valve of the spool type which is quick and sensitive in operation and positive in its action.

15 Other objects will be in part obvious and in part pointed out hereinafter.

The invention consists of the combinations of elements, features of construction and arrangement of parts having the general mode of operation substantially as hereinafter described and more particularly pointed out in the appended claims and illustrated in the accompanying drawing, in which—

20 Figure 1 is a longitudinal view in elevation and partly in section of so much of a rock drill as will serve to illustrate the invention,

25 Figure 2 is a view similar to Figure 1 and in which the reciprocatory parts are shown in another position.

Referring to the drawing, the invention 30 is shown embodied in a rock drill having a cylinder A in which is arranged a reciprocatory piston B for delivering blows on a drill steel (not shown). A front cylinder washer C is disposed within the front end

35 of the cylinder A and has a bore D to receive slidably a fluted forward extension E of the piston B. The back end of the cylinder A is sealed by a back cylinder washer F which also serves to centralize a back head

40 G arranged at the back end of the cylinder A. Any suitable means may be provided for securing the back head G to the cylinder A, but such means preferably consist of side rods or bolts (not shown) arranged on opposite sides of the drill.

45 Rotary motion of the piston B is in this instance accomplished by a rifle bar H which engages the piston B in the usual manner. A ratchet head J preferably

50 formed integral with the rifle bar H carries a plurality of spring actuated pawls K. The pawls K are so arranged that they will pass freely over teeth L formed in a ratchet

ring O while the piston is traveling in one direction, but will engage said teeth while 55 the piston is traveling in the opposite direction and thus hold the rifle bar stationary and cause the piston to rotate.

Secured to the cylinder A in any suitable manner, as for instance bolts P, is a valve 60 chest Q comprising a bottom plate R and a top plate or cap S. A throttle valve T, preferably arranged within the cap S of the valve chest Q, controls the admission of pressure fluid to the machine. The pressure 65 fluid is exhausted from the cylinder A through a free exhaust port U preferably formed in the cylinder intermediate its ends and is controlled by the piston B.

In accordance with the present invention, 70 a pressure chamber V is formed in the cap S and a similar chamber W is formed in the plate R to receive a distributing valve X. The valve X is of the spool type and has a central flange Y extending at its periphery 75 into an annular supply chamber Z which communicates with the throttle valve T through passages R' and S' formed in the plate R and the cap S respectively. In this instance sides b and c of the flange constitute actuating and holding faces against which pressure fluid may act for throwing the valve and for holding it in thrown position. In addition to serving as actuating 80 and holding faces, the faces b and c also 85 control the admission of pressure fluid to the rear and front ends of the cylinder through supply passages d and e respectively.

In order to facilitate throwing of the valve in one direction, a passage f is formed 90 from the forward end of the cylinder A to the chamber W for admitting pressure fluid from the cylinder into said chamber to act against a face g for augmenting the pressure fluid acting against the face b of the flange Y for throwing the valve and holding it in thrown position. A similar passage h provides communication between the rear end of the cylinder A and the chamber 95 V for admitting pressure fluid into said chamber to act against a face j at the other end of the valve for augmenting the pressure fluid acting against the face c of the flange Y for throwing the valve to its opposite position and for holding the valve in 100 thrown position.

105

In order to further facilitate the throwing of the valve, a plurality of small passages *k* are formed through the flange *Y* to communicate at their ends with annular passages *o* and *p* formed in the cap *S* and the plate *R* respectively to encircle the pressure chambers *V* and *W*. In this instance, passages *q* and *r* leading from the chambers *V* and *W* respectively to the atmosphere are formed in the valve chest to prevent the forming of a cushion while the valve is being thrown.

In the operation of the device, with the parts shown in the position in Figure 1, pressure fluid flowing from the throttle valve *T* into the annular chamber *Z* will pass over the face *c* of the valve *X* and thence into the annular passage *o* and through the supply passage *e* into the front end of the cylinder and drive the piston *B* rearwardly. During the rearward travel of the piston *B*, the passage *f* will be uncovered and permit a portion of the pressure fluid to flow therethrough into the chamber *W* to augment the pressure acting against that part of the face *b* of the valve *X* which extends into the annular groove *Z* for throwing the valve. After the piston *B* covers the exhaust port *U* and while the valve is still in the position shown in Figure 1, the pressure fluid leaking through the passages *k* will flow into the rearward end of the cylinder *A*. In this way equal pressures are obtained on opposite sides of the flange *Y*. Such equalization of pressures on opposite sides of the flange will cause the valve to move to a neutral position. As the piston continues rearwardly the pressure fluid acting against the face *b* of the flange *Y*, assisted by the compression formed in the rear end of the cylinder after the passage *h* is covered by the piston will act against the face *b* and throw the valve to the position shown in Figure 2. In this position of the valve, pressure fluid will flow across the face of the valve into the annular passage *p* thence through the supply port *d* into the rearward end of the cylinder and drive the piston forwardly.

As the piston advances on its forward stroke, the passage *h* is uncovered and pressure fluid is admitted into the chamber *V* to act against the face *j* of the valve. At the same time, pressure fluid will leak through the passages *k* into the annular passage *o* and, as during the rearward stroke of the piston, augments the compression formed in the front end of the cylinder to act against the face *c* of the flange *Y* for throwing the valve in the opposite direction, thus completing the cycle of operations.

The advantages of this invention reside in the fact that a valve constructed in this manner requires only a slight travel to sup-

ply pressure fluid in sufficient quantities to the cylinder. Another desirable advantage is that the valve is quick and positive in action.

I claim:

1. In a fluid actuated rock drill, the combination of a cylinder with a reciprocatory piston, a valve chest having pressure chambers, annular chambers encircling the pressure chambers, a valve located in the pressure chambers and annular chambers, actuating and holding faces at each end of the valve, a central flange on the valve to control the admission of pressure fluid from a source of supply to the annular chambers, and supply passages affording communication between the annular chambers and the ends of the cylinder for conveying pressure fluid to the cylinder.

2. In a fluid actuated rock drill, the combination of a cylinder with a reciprocatory piston, a valve chest having pressure chambers, annular chambers encircling the pressure chambers, a valve located in the pressure chambers and annular chambers, actuating and holding faces at each end of the valve, a single flange on the valve to control the admission of pressure fluid from a source of supply to the annular chambers, actuating and holding faces on each side of the flange against which pressure fluid may act for throwing the valve and holding it in thrown position, and supply passages affording communication between the annular chambers and the ends of the cylinder for conveying pressure fluid to the cylinder.

3. In a fluid actuated rock drill, the combination of a cylinder with a reciprocatory piston, a valve chest having pressure chambers, annular chambers encircling the pressure chambers, a valve located in the pressure chambers and annular chambers, actuating and holding faces at each end of the valve, a single flange on the valve to control the admission of pressure fluid from a source of supply to the annular chambers, actuating and holding faces on each side of the flange, passages through the flange to provide communication between the annular chambers, and supply passages leading from the annular chambers to the cylinder for conveying pressure fluid to the cylinder.

4. In a fluid actuated rock drill, the combination of a cylinder with a reciprocatory piston, a valve chest having pressure chambers, annular chambers encircling the pressure chambers, a valve located in the pressure chambers and annular chambers, actuating and holding faces at each end of the valve, a single flange on the valve to control the admission of pressure fluid from a source of supply to the annular chambers, actuating and holding faces on each side of the flange, passages through the flange for the admission of pressure fluid there-

through to equalize the pressure on both sides of the flange, supply passages leading from the annular chambers to the ends of the cylinder, passages controlled only by the piston for conveying pressure to the pressure chambers to facilitate reciprocation of the valve and for holding the valve, and passages leading from the pressure chambers to the atmosphere to prevent cushioning in that chamber toward which the valve ¹⁰ is being thrown.

In testimony whereof I have signed this specification.

GEORGE W. HULSHIZER.
